UNITED STATES PATENT OFFICE

ELMER BASSETT, OF SHELBYVILLE, INDIANA.

WATER-POWER PLANT.

1,157,922.

Specification of Letters Patent. Patented Oct. 26, 1915.

Application filed October 10, 1914. Serial No. 866,125.

To all whom it may concern:

Be it known that I, ELMER BASSETT, a citizen of the United States of America, residing at Shelbyville, Shelby county, Indiana, United States of America, have invented certain new and useful Improvements in Water-Power Plants; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to water power plants and has for its object to provide a simple and efficient water wheel to which the water of a stream is conveyed or guided and which wheel is provided with mechanism for raising and lowering it according to the level of the stream, such mechanism being pneumatic mechanism actuated by compressed air from a suitable source, preferably from a tank in which air has been compressed by the power generated by the wheel, as will hereinafter be more particularly described and pointed out in the claims.

Referring to the drawings, in which like parts are similarly designated—Figure 1 is a plan view of the power plant. Fig. 2 is a vertical section through the wheel. Fig. 3 is a view partly in elevation and partly in section along the axis of the wheel. Fig. 4 is a detail sectional view of one of the pneumatic pistons, and Fig. 5 is a section through a three-way cock controlling the air to the piston.

Either partly or entirely extending across the stream from one bank to the other, I provide a cement bottom 1 provided with guide walls 2 at an angle to one another, at the apex of which I form piers 3 of sufficient width apart for the wheel 4. The guide walls 2 are preferably slightly above the normal water level, so that when the water rises above them it may flow over the tops of these walls without necessitating the lifting of the water-wheel, while during freshets means are provided, as will hereinafter be explained for lifting the wheel.

The wheel is mounted in bearings 5 that are carried by pneumatic pistons 6 operating in pneumatic cylinders 7 in the piers 3. These pistons are guided at their upper ends by long extensions 8 passing through

guides 9 on top of the piers 3. At the bottom of the cylinders 7 enter air pipes 10 which are branches of a single pipe 11 from an air storage tank 12 supplied with air by 60 a compressor or pump indicated at 13, which pump is driven by a belt 14 actuated by an electric motor 15 supplied with electricity from a generator 16 driven by the water wheel 4.

The shaft of the wheel 4 is connected to an extensible shaft 17 universally jointed at its ends 18 and 19 and forming the flexible shaft connection between the wheel and the line shaft 20 mounted on piers 21 in the 70 shallow portion of the stream or on the shore as the particular nature of the stream may require or demand.

I provide on the line-shaft 20, a suitable clutch 22 operated by a lever 23 whereby 75 the power shaft may be disconnected from the water wheel.

Between the pipes 10 and 11 is a three-way valve 24 by means of which air from the tank 12 can be admitted to pipes 10 and 80 cylinders 7, can be cut off entirely, or can be vented to the atmosphere, whereby the raising and lowering of the pistons 6 is effected and controlled. In addition to the valve 24 there is a valve 25 in each pipe 10 85 to individually control the admission of air to the cylinders for the purpose of admitting more air to one cylinder than the other in case the rate of rise of the pistons should not be the same from any source.

A suitable electric switch 26 is provided in the electric power line 27 to disconnect the motor 15 operating the pump.

In order to maintain the wheel 4 at the desired height, the pistons 6 are provided 95 with notches 28 into which may engage a pawl 29 mounted on the pier 3, to support the pistons in their raised positions, see dotted line position, Fig. 4.

The operation of the plant is as follows: 100 The water, when the stream is at an ordinary level will be guided between the guide walls 2 to the water wheel 4 to the piers 3, to drive the water wheel 4 and shafts 17, 20. When the water level raises, the walls 2 are sufficiently low to permit the water to pass over them without prejudicially affecting the operation of the wheel, and the wheel 4, when necessary, is raised by opening valve 24 and admitting compressed air through 105 pipes 10 to cylinders 7 below the pistons 6, thereby raising these pistons and the water

wheel 4 mounted therein. Meanwhile, the pawls 29 have been moved to the dotted line position shown in Fig. 4 and when the pistons have been raised to a sufficient height 5 the air is cut off and the pistons settled quietly to the position determined by the pawls 29 and notches 28, the settling of the pistons being due to the leakage of air from the cylinders.

10 By using the pawls 29 to support the pistons at proper elevation it becomes unnecessary for me to use extreme care in packing the pistons and cylinders to prevent leakage.

I claim—

15 1. In a water power plant, the combination with a water wheel, of pneumatic pistons and cylinders for raising and lowering said wheel, a pump for supplying compressed air to said pistons, an electric motor 20 for driving said pump and an electric generator for supplying current to said motor driven from said wheel.

25 2. In a water power plant, the combination with a water wheel, of pneumatic pistons and cylinders for raising and lowering said wheel, compressed air conduits communicating with said cylinders, an air supply pipe, a three-way valve adapted to alternately connect the latter to the conduits and 30 to vent said conduits to the atmosphere, an air compressor connected with said pipe, an electric motor for operating the compressor, and an electric generator driven by the wheel for supplying current to the motor.

3. In a water power plant, the combination 35 with a water wheel, of pneumatic pistons and cylinders for raising and lowering said wheel, said pistons having guided extensions and notches therein, pawls arranged for engagement in said notches, a 40 three-way valve to control a simultaneous admission of air to said cylinders, and valves to independently control the admission of air thereto.

4. In a water power plant, the combination 45 with a water wheel, of pneumatic pistons and cylinders for raising and lowering said wheel, said pistons having guided extensions and notches therein, pawls arranged for engagement in said notches, a three-way valve 50 to control a simultaneous admission of air to said cylinders, valves to independently control the admission of air thereto, a line shaft, a universal connection between the water wheel and said shaft, said connection 55 capable of extension, a clutch in the line shaft, an electric generator driven by said line shaft, a pump for supplying compressed air to said pistons, and an electric motor for driving said pump, said motor supplied with 60 current from said generator.

In testimony that I claim the foregoing as my invention, I have signed my name in presence of two subscribing witnesses.

ELMER BASSETT.
